Application March 23, 1935, Serial No. 12,692

7 Claims. (Cl. 36—29)

This invention relates to shoes and has special reference to a pneumatic tread shoe.

One important object of the invention is to provide a novel arrangement of shoe sole having an air filled sac or bag interposed between the insole of the shoe and the tread portion of the sole.

A second important object of the invention is to provide an improved sole of this kind wherein the air sac is supported all around by the side walls of a recess formed in the upper surface of the sole.

A third important object of the invention is to provide a novel shoe having an arrangement of air filled sac in its sole which will eliminate the necessity for arch supporters and, in almost all cases will eliminate the necessity of building up shoes to meet individual requirements due to weak or flat feet.

20 A fourth important object of the invention is to provide a novel shoe of this character adapted to provide a gentle beneficial massage and stimulation for the foot when walking.

A fifth important object of the invention is 25 to provide a novel form of arrangement for expansion and contraction of the leather of the innersole.

With the above and other objects in view, the invention consists in general of certain novel 30 details of construction and combinations of parts hereinafter fully described, illustrated in the accompanying drawings and specifically claimed.

In the accompanying drawings like characters of reference indicate like parts in the several 35 views, and:—

Figure 1 is a side elevation of a shoe constructed in accordance with this invention.

Figure 2 is a bottom plan view of the shoe.

Figure 3 is a bottom plan view of the sole with 40 the tread layer removed.

Figure 4 is a longitudinal section of the lower part of the shoe on the line 4—4 of Figure 2.

Figure 5 is a view similar to Figure 4 but with the air sac removed.

45 Figure 6 is an enlarged detail section of the lower part of the shoe on the line 6—6 of Figure 1.

Figure 7 is a plan view of the insole removed from the shoe.

50 In the invention as here disclosed there is shown a shoe having an upper 10 and a sole consisting of an upper part indicated in general at 11 and a tread layer 12 provided with a heel 13. The tread layer 12 is provided with a welt 14 for purposes presently to be described.

The upper part 11 includes a peripheral rim, the sides 15 of which may be made in the form of spacing strips of felt or other like yieldable or non-yieldable material as desired, while the toe portion 16 and the heel portion 17 of the rim 5 are formed of relatively rigid leather spacing strips of non-yieldable material. The upper edge of this rim is formed by an upper welt 18 to which the shoe upper is attached. A thin leather strip 19 covers the outsides of the strips 15, 16 10 and 17 to make a finish for the outside of the upper section of the sole. Any of the strips 15, 16 and 17 can be made either of yieldable or non-yieldable material. This strip 19 has an upper flange part 20 secured below the welt 18. 15 A lower flange part 21 is secured between the lower welt 14 and the members 15, 16 and 17. A filler strip 21' is arranged between the sole 12 and the inner parts of members 15, 16 and 17. Obviously the various parts of the shoe are 20 held together in the usual manner as by stitching or other means such as employed ordinarily in the construction of shoes and form no part of this invention.

It will now be plain that the sole, when the 25 tread section is sewed to the upper part, is provided with a recess in its upper surface. This recess is covered by a layer 22 of cork or other suitable material. In the recess 22' of the sole 30 is held a sac or bag 23 of rubber or other suitable material impervious to air and this sac is provided with a filling valve 24 which extends down through a suitable opening in the tread layer 12, the opening being located just forward of the front face or breast of the heel 13. By 35 means of the valve 24 the sac 23 may be inflated by an ordinary tire pump. It will be observed that the rim prevents longitudinal expansion of the sac but permits a slight lateral expansion of the sac due to the compressibility of the felt 40 sides 15.

Resting on the cork layer 22 is an insole 25 of leather or other suitable material. In order to provide against warping due to expansion of the leather of the innersole because of heat or moisture of the foot or of weather conditions and to permit such expansion and contraction of the insole as will be necessary, the portion of the insole which lies beneath the ball of the foot and from there on forward is provided with relatively 45 large perforations 26 and relatively small perforations 27. These perforations may be of one size if desired. The lower ends of these perforations are preferably closed by a thin filter strip 28 to prevent the cork filler from pushing up through 50 55

the perforations and so into the shoe. The perforations may be made so small that the cork filler will not push through them in which case the covering strips may be omitted. This insole 5 can also be used in an ordinary shoe.

When in use, the somewhat flexible tread layer yields and transmits the pressure to the sac which, due to the compressibility of the air in said sac, absorbs the shock of walking or running just as a pneumatic tire absorbs the shock of a 10 wheel running over rough ground. Moreover, the air sac effects a massaging of the sole of the foot. As the heel of the foot strikes the ground, there is a compression of air in air sac which 15 absorbs this shock and then air flows to the forward portion of the air sac, effecting the middle or shank and forepart of the foot.

There has thus been provided a simple and efficient device of the kind described and for the 20 purpose specified.

It is obvious that changes may be made in the form and construction of the invention. It is not therefore desired to confine the invention to the exact form herein described and shown but it is 25 desired to include all forms covered by the appended claims.

What is claimed is:—

1. A shoe having an outsole, and an insole, 30 spacing strips arranged peripherally of said insole and between the insole and outsole providing a cavity therebetween, and an air filled sac filling said cavity, said spacing strips being formed of yieldable material along the side of the insole and outsole, and of substantially rigid material 35 along the end portions thereof.

2. A shoe having an outsole, and an insole, spacing strips arranged peripherally of said insole and between the insole and outsole providing a cavity therebetween, and an air filled 40 sac filling said cavity, and having a filling valve extending through the outsole, said spacing strips being formed of yieldable material along the side of the insole and outsole, and of substantially rigid material along the end portions thereof.

45 3. A shoe having an outsole, and an insole, spacing strips arranged peripherally of said insole

and between the insole and outsole providing a cavity therebetween, and an air filled sac filling said cavity, said spacing strips being formed of felt along the sides of the insole and outsole and of leather along the end portions thereof. 5

4. A shoe having a heel, an outsole, and an insole, spacing strips arranged peripherally of said insole and between the insole and outsole providing a cavity therebetween, and an air filled sac filling said cavity, said spacing strips being 10 formed of yieldable material along the side of the insole and outsole, and of substantially rigid material along the end portions thereof, and a filler valve for said sac arranged near the forward part of said heel. 15

5. A shoe having a heel, an outsole, and an insole, spacing strips arranged peripherally of said insole and between the insole and outsole providing a cavity therebetween, and an air filled sac filling said cavity, said spacing strips being 20 formed of felt along the sides of the insole and outsole and of leather along the end portions thereof, and a filler valve for said sac arranged near the forward part of said heel.

6. A shoe having an outsole, and an insole, 25 spacing strips arranged peripherally of said insole and between the insole and outsole providing a cavity therebetween, and an air filled sac filling said cavity, said spacing strips being formed of yieldable material along the side of the insole 30 and outsole, and of substantially rigid material along the end portions thereof, said insole including an upper layer of leather and a lower layer of cork.

7. A shoe having an outsole, and an insole, 35 spacing strips arranged peripherally of said insole and between the insole and outsole providing a cavity therebetween, and an air filled sac filling said cavity, and having a filling valve extending through the outsole, said spacing strips being 40 formed of yieldable material along the side of the insole and outsole, and of substantially rigid material along the end portions thereof, said insole including an upper layer of leather and a 45 lower layer of cork. 45
